THERMAL CUT-OUT

Hugh A. Triplett, Wilmette, and Sigurd I. Lindell,
Chicago, Ill., assignors to Schweitzer & Conrad,
Inc., Chicago, Ill., a corporation of Delaware

Application April 25, 1934, Serial No. 722,280

41 Claims. (Cl. 200—142)

The present invention relates to thermal protection of transformers and the like. Whereas the specific disclosure relates to the protection of high tension transformers of the potential type, it is to be understood that the invention is not limited to any particular type or voltage of transformer, nor in fact is the invention to be limited to the protection of transformers only. Certain features and combinations herein disclosed are applicable to the same or analogous service in other equipment or apparatus.

In known transformer installations, fuses and circuit breakers on the high tension side are at present employed for the twofold purpose of first protecting service in the event of a transformer winding or bushing failure, and, second, protecting the transformer from the thermal effects of a short circuit or overload occurring on the load side of the transformer.

20 A condition of partial breakdown may occur in a transformer. This may arise through breakdown of the insulation between adjacent turns occurring, for example, in the high tension winding. The primary fuse or circuit breaker will not operate if the current drawn does not exceed the rating of the fuse or circuit breaker. That is to say, the actual current flowing may not exceed the rating of the transformer, but the heat generated in the short circuited coil is localized and 25 may be very considerable. This heat is imparted to the oil, raising it to the flash point. The fault tends to proceed to the short circuit stage because the heating tends to destroy the insulation. Arcing which occurs at the instant of final breakdown is capable of igniting the oil vapors, resulting in an explosion and fire. This is a hazard to life and property, which the fuse or circuit breaker of commercial type is incapable of preventing. To avoid explosions from such causes, the transformer must be disconnected before the 30 temperature of the oil is raised to the flash point.

40 The present invention aims to provide a novel circuit interrupter provided with controlling means, and organized to interrupt the circuit when the temperature of the oil of the transformer or the like exceeds a predetermined value.

We are aware that it has heretofore been proposed to provide a thermal control for a conventional circuit breaker. Such a circuit breaker 45 may also be controlled by excess current flow, or be hand controlled.

The preferred form of the present invention aims, however, to provide a simplified and compact form of circuit interrupter which shall be 50 not only less expensive than conventional forms

of circuit breakers, but better adapted to the particular service.

The present invention is particularly concerned with a compact circuit interrupter of the single operation type, intended to be enclosed either within the transformer shell or in a separate housing and to be controlled by the temperature of the transformer oil.

In the copending application of Beckett and Lindell, Serial No. 721,706, filed April 21, 1934, 10 there is disclosed a form of thermally controlled circuit interrupter adapted to be disposed in thermal contact with the oil and disposed in the transformer casing, and being of the shop re-loadable type.

15 The present invention aims to improve the aforesaid device and devices of the aforesaid class or type.

One of the chief objects of the present invention is to provide a device of this class or type 20 with the features of thermal control and of circuit interruption individually organized to a higher degree, and so coordinated as to ensure reliability and certainty of operation at the desired temperature and with adequate interrupting capacity 25 to withstand service requirements.

Another object of the invention is to provide 30 a circuit interrupter wherein the contacts of the device are releasable by external means, preferably mechanical in character and applied or positioned exterior to the assembly of the interrupter.

A further object of the invention is to provide 35 a sealed interrupter unit having automatically separable contacts locked in engagement with a separate thermal element with a mechanical transmission of motion to unlock or release the contacts for automatic separation. The thermal element may be remotely situated, if desired. The transmission, instead of being mechanical, may be a fluid pressure transmission, or an electric transmission, but, in any case, the unlocking or release of the contacts is effected by an externally applied thermal element assembly, and without unsealing the interrupter unit.

40 A further object of the invention is the provision of a power element which is applied under control of the thermal element to the unlocking or release of the automatically separable contacts. Preferably, this power-element is a spring 45 which has two stages of motion, the first stage ensuring the complete release of the thermally controlled element, and the second stage unlocking or releasing the contacts. By this provision, the two phases of operation are separated to 50 55

5 avoid interference of one with the other, and it permits of delivering a blow or thrust to the release means after complete release from possibility of thermal change or other factor interfering with full actuation of the thermally controlled means.

Another object of the invention is to provide a thermally controlled circuit interrupter of great sensitivity and definiteness of operation, and of 10 great interrupting capacity in small space.

Another object is to provide a thermal actuating mechanism capable of rapid response to temperature changes in the circum-ambient medium.

15 Another object is to provide means under thermal control for simultaneous control of the actuation of a plurality of circuit interrupters.

A further object is to provide a novel form of 20 automatic circuit interrupter of high interrupting capacity in small space and arranged for mechanical release all in a fluid tight housing. Such a circuit interrupter may be submerged in oil and housed in a metal casing without effect upon its interrupting capacity.

25 Another object of the invention is to provide a suitable organization of interrupter and thermal control with a mechanical transmission allowing separation and separate housing of the interrupter and the element.

30 Another object of the invention is to provide a circuit interrupting device either for individual operation or gang operation, which may be controlled by any selected phenomenon. The circuit interrupter mechanism, with its necessary structure and environment for operation, and suitable 35 governing mechanism providing control at a large mechanical advantage, may advantageously be employed wherever the controlling phenomenon, or its responsive element, is designed to produce

40 or provide only a small operating force. Thus, for example, the circuit interrupter with its detent, operating mechanism therefor, and control mechanism therefor, might be governed by a pressure sensitive element, instead of a thermally sensitive element. Or it might be controlled by an 45 element responsive to any other desired or selected phenomenon, either automatically or under hand control.

Other and further objects of the invention will 50 become apparent from the following specification, drawings and claims.

Now in order to acquaint those skilled in the art with the manner of constructing and operating a device embodying our invention, we shall 55 describe, in conjunction with the accompanying drawings, a specific embodiment of the invention.

In the drawings:

Figure 1 is a vertical longitudinal section 60 through one embodiment of our invention;

Figure 2 is a front elevational view of the circuit interrupter shown in Figure 1;

Figure 3 is a fragmentary vertical section 65 through the thermally sensitive element and the interrupter contact, on an enlarged scale;

Figure 4 is a transverse section through the clutch element and movable contact, substantially on the line 4-4 of Figure 3;

Figure 5 is a side elevational view, partly in 70 section, of the thermally sensitive element and the leverage system for providing a mechanical advantage;

Figure 6 is a top plan view of the element shown 75 in Figure 5;

Figure 7 is a vertical section, partly in elevation, of the circuit interrupter installed in a different manner from that shown in Figure 1;

Figure 8 is a longitudinal section, on an enlarged scale, of the push rod and its seal, which is employed to actuate the releasing device in the interrupter shown in Figure 7 and in Figure 9;

Figure 9 is a view, partly in side elevation and partly in vertical section taken along the line 9-9 of Figure 10, showing the elements of the 10 installation in which a plurality of circuit interrupters are employed;

Figure 10 is a side elevational view of the tripping spring mechanism and the release therefor; and

15

Figure 11 is a fragmentary cross sectional view taken on the line 11-11 of Figure 10, showing one of the spring actuated trip hammers.

Referring now to Figures 1 to 6, inclusive, the transformer tank 1 contains the windings of 20 a transformer submerged in a body of oil 5. The interrupter 1 is mounted upon the insulators 8 and 9 through suitable split clamp contacts 10 and 12, these contacts having clamping lugs such as 13-13, drawn together by bolts provided with 25 clamping nuts 14-14 to provide good electrical contact and solid mechanical support for the interrupter 1. The insulators 8 and 9 carry the clamping contacts 10 and 12 and the insulators are, in turn, supported upon a suitable frame, 30 which may be a channel member 15, disposed vertically at one side wall of the tank 1. The contacting clamps 10 and 12 are preferably formed electrically integral with connecting lugs 16-16, one of which may lead to the line connection and 35 the other to the transformer winding.

The interrupter comprises an intermediate insulating sleeve 17, which may be of bakelized fiber, or glass, or any other suitable material, with metallic ferrules such as 18-19 cemented, or 40 otherwise bonded upon the ends of the sleeve. These ferrules are arranged to pass axially within the clamps 10 and 12 and be engaged mechanically and electrically by said clamp. The ferrule 18 is provided with a reduced piloting portion at 45 its lower end to assist in conducting the contacting portions of the ferrules into the corresponding clamp contact. The ferrules and stationary contacts may obviously be arranged in any other suitable fashion for mechanically and electrically 50 supporting the interrupter properly in position and connection. The upper ferrule 19 (see particularly Figure 3) has an extension beyond the end of the sleeve 17 within which the upper contact 20 is supported. This extension 22 of the 55 upper ferrule is threaded at its lower end to receive the insulating bushing 23 which, as will be pointed out later, provides an arc constricting passageway and a passageway for directing the flow of arc extinguishing fluid through the arc. The 60 bushing 23 has a flange which is threaded to an internal thread 24 within the extension 22, and the said bushing is recessed to receive the lower end of the sleeve 25 of insulation. The sleeve 25 serves the double function of forming a part of a 65 clutch or holding means for holding the movable terminal 26 in contact with the stationary terminal 20. The movable contact 26 is preferably a separable tip at the upper end of a rodlike plunger 28, which rodlike plunger 28 is connected 70 at its lower end to a head or spring support 29 connected to the upper end of the tension spring 30, the lower end of which spring is anchored in the lower ferrule 18. The spring head 29 is connected by a flexible stranded conductor 32 to 75

75

the said lower ferrule 18. An annular liquid director is supported upon a sleeve 34 which is slidably mounted on the rod 28. The junction of the rod 28 and the tip 26 provides a shoulder 35 which engages the sleeve 34 when the rod 28 is drawn down by the spring 30. By this construction the rod and its arcing tip are first drawn down through the sleeve 25 and the bushing 23 before the liquid director 33 is picked up. The liquid director 33 fits fairly closely within the lining sleeve 36 provided at the upper end of the main sleeve 17. This lining sleeve 36 performs the double function of first increasing the thickness of insulation to prevent puncture between the live parts within the sleeve 17 and the ferrule 19 outside of the same when interruption progresses to the point of creating a potential difference between the parts. The sleeve 36 further provides a removable liner which, if damaged by the arc, may be removed and replaced without the necessity of replacing the main sleeve 17, which might otherwise be injured by the arc.

The upper end of the ferrule extension 22 has communicating therewith an expansion and condensing chamber 37 which is closed off from atmosphere and communicates only with the upper end of the ferrule extension 22. Within the expansion and cooling chamber 37, the walls of which are preferably formed of metal throughout, although this is optional, there is disposed a mass of subdivided metal to form condensing and cooling means, this mass 38 preferably consisting of a large number of circular plates apertured at the center and clamped in spaced, parallel relation, upon a central mounting rod or sleeve. The rod upon which the plates 38 are mounted is preferably centrally located and is indicated at 39. To the lower end of the rod there is connected a spring contact member 20 consisting of a sleeve, the upper end of which is threaded upon the rod 39 and the lower end of which is slotted to provide a plurality of contact fingers extending below the lower end of the rod 39, these spring fingers being further reinforced by a garter spring 21, that is, a coil spring lying in a groove on the outer periphery of the spring fingers of the sleeve 40, and tending to constrict the same. The lower end of the rod 39, which lies within the sleeve 20 and above the tips of the spring fingers, constitutes an arcing tip 39a. It functions largely to centralize and position the spring fingers of the sleeve 20 and provides an arc terminus having sufficient section and surface during the circuit interrupting process. The upper end of the arcing tip 26 is preferably chamfered off to correspond to the funnel-like socket formed by the spring fingers of the sleeve 20. The body of the interrupter is preferably provided with an arc extinguishing material, herein shown as liquid, having suitable arc extinguishing and insulating properties, the level of the liquid preferably being approximately at or below the bushing 23. The level of the liquid may be considerably varied, but it should be in such position as to act promptly upon the arc as soon as the same is confined within the sleeve 25 and the bushing 23. For this purpose it may stand at approximately the top of the bushing 23.

70 We contemplate also the utilization of a solid arc extinguishing material instead of the liquid or, in fact, any suitable form of arc extinguishing material which will produce the desired effect hereafter described in connection with a 75 statement of the operation of the present device.

Operation of the circuit interrupter

The circuit interrupter thus far described, assuming that the movable and stationary contacts are in engagement and that current is being conducted through the device, will operate to interrupt the flow of current when the movable terminal is released and permitted to descend under the action of the tension spring 30. As soon as the contacts separate an arc is formed and, as the movable terminal retreats into the tubular passageway, arc extinguishing material is brought into play, both because the interior surfaces are substantially wet with the same and because the lowering of the rodlike member 28 instantly results in extending the arc into position where the heat thereof will evaporate some of the liquid, creating a fluid pressure below the bushing 23, so that as the rodlike member 28 descends, drawing the arc into the restricting passageway of the sleeve 25 and the bushing 23, the metal vapor and ionized gases which may be contained within the arc are driven longitudinally upward into the condensing and cooling chamber 37, where they are out of the influence of the arc, and further flow of arc extinguishing medium occurs. When the rodlike member 28 has descended to the point where the shoulder 35 engages the sleeve 34, the liquid director 33 tends to descend and the liquid below the director is projected upward into the space where the arc is formed and maintained. The scavenging action of the flow of the gaseous medium endwise of the arc through the restricted passageway which confines the arc laterally, and the increase in pressure of the said medium, is highly effective in extinguishing the arc and stopping the flow of current. It is to be understood that the aforesaid scavenging action may be secured by the use of a solid arc extinguishing material, which, under the heat of the arc, yields a gaseous medium for effecting the same purpose. The gaseous medium is driven up into the space 37, where it tends to be cooled and condensed.

The contraction of the spring 30 carries the 45 arcing tip down into the liquid after current flow ceases, further interposing a dielectric medium between the terminals.

The device is intended to be reset or reloaded in the shop or factory after a single operation, 50 but we do not wish to confine the invention to that specific procedure. The employment of a completely closed unit in a situation such as herein illustrated is highly desirable, inasmuch as the products of the arc or the arc extinguishing materials are not brought into contact with the insulating oil 5, and hence do not tend to contaminate the same, even by repeated operations.

The detent or clutch mechanism

The movable rodlike member 28 is held in circuit-closing position, that is, in engagement with the stationary contact 20, by a clutch or detent which is formed in part by the sleeve 25.

The upper end of the rod 28 or the arcing tip 26 has a peripheral groove 41 which registers with a pair of diametrically disposed openings 40-40 in the sleeve 25. The sleeve 25 is flattened or slabbed off on opposite sides where the 70 openings 40-40 are formed, and a holding member in the form of a yoke or U-shaped clamp 43 has its arms 44-44 overlying the flat sides of the sleeve 25. The wall thickness of the sleeve 25 at the flattened portions and the diameter of the 75

balls 42-42 is so proportioned that when the arms 44-44 overlie the openings 40-40 the balls 42-42 are pressed into the groove 41 and clutch the tip 26 to the sleeve 25.

5 The faces of the arms 44-44 which are turned toward the sleeve 25 are, adjacent their outer ends, flat planar surfaces, but these arms have recesses 44'-44' which may be brought into register with the balls 42-42 by shifting of the 10 fork or clamp member 43 to the left, thereby to release the clutch between the sleeve 25 and the rod 26. Thus the member 43 constitutes a clutch releasing member, or a detent releasing member for releasing the movable contact 26 to allow 15 the spring 30 to operate the device.

20 The normal position of the parts is shown in Figures 3 and 4, and it is to be understood that when the member 43 is moved to the left, as viewed in Figure 4, to the point where the recesses 25 44'-44' register with the openings 40-40, the balls 42-42 will be driven out of the groove 41 by the tension of the spring 30 and can drop into the recesses 44'-44', thereby allowing the arcing tip 26 and associated parts to be released. This 25 release member 43 is actuated by the power element P which I shall now describe. The power element P is controlled, directly or indirectly, by the thermostatic responsive element T which will be described later.

30 *The power element*

35 A side wall of the ferrule extension 22 is apertured transversely and threaded to receive a threaded nipple or stud. The power element comprises a tubular cylindrical housing member 45 having an integral threaded neck portion 46 threaded into the opening in the side wall of the ferrule extension 22, as shown in Figs. 3 and 4. The opposite end of the barrel or tubular housing member 45 is formed with an open end which is closed by a cap member 47, threaded to the end of the barrel and sealed as by a gasket 48. The central part of the head member 47 is provided with a threaded opening 49 through which is 40 threaded the stem 50 of the thermally sensitive element T. Within the barrel 45 there is provided a heavy coil spring 52 which is compressed between the head 47 and a spring follower 53. The spring follower has a tubular plunger 54 guided within the hollow neck 46. At its outer or 45 left-hand end, as seen in Figures 3 and 4, this hollow plunger 54 has a reduced diameter. The reduced diameter portion and the main portion of the plunger 54 meet at an annular shoulder which, as shown in Figure 3, normally lies within the neck 46. The outer end of the reduced portion of the plunger 54 extends through an opening in the release member 43, as indicated at 55, and the release member is held on the reduced 50 portion 55 by a split ring or other means forming a shoulder upon the outer end of the reduced portion 55 beyond the fork of the release member 43. As herein shown, a groove is formed in the outer periphery of the reduced portion 55 and a wire 55 ring 56 is contracted into the groove to form a shoulder on said member 55. The outer end of the reduced member 55 is counterbored to provide a shoulder, as indicated at 57 in Figure 4, and a cross-pin 58, to which is connected a tension link 59, is seated in said counterbore 57 against the shoulder at the end of the same. This tension link 59 is preferably a thin, flat strip which extends through the hollow plunger 54 and has its rear end held by the anchorage provided 60 by a member providing a mechanical advantage,

this member being indicated by the reference letter M in Figures 3 to 6. The mechanical advantage device M anchors the tension link 59 to the head 47 of the barrel member 45 under the control of the thermostatically controlled element 5 T, as will be described later.

65 The operation of the power device is as follows: The compressed coil spring 52 contains a very considerable power which is applied to two purposes. The first purpose is to free the tension link 59 from the restraint of the mechanical advantage device M and the thermally responsive device T, as will be described later, and the second function is to operate the clutch release device 43. The reduced diameter portion 55 of the 15 plunger 54 is adapted to slide freely in the hole through the release member 43, hence the spring 52 may expand and drive the follower 53 and plunger 54 to the left until the shoulder on said plunger 54 engages the release member 43, whereupon the release member 43 is carried to the left, bringing the releasing recesses 44' in register with the openings 40 and allowing the clutch balls 42 to release the plunger 26. It is to be observed that the barrel 45 is united in a fluid-tight joint with the ferrule extension 22. The threaded neck 46 has a shoulder which clamps a sealing gasket against a suitable seat surrounding the opening in the ferrule extension. The head 47 is secured in fluid-tight fashion to the end of 30 the barrel 45 by means of the interposed gasket held by the screw threads. The anchorage of the threaded stem 50 in the head 47 is rendered fluid-tight by a conical shoulder 60 which seats in a conical seat and forms a tight closure, like a 35 valve, sealing off the opening through the head 47. A hollow shield member 62 formed in the shape of a perforated cup or guard, has its bottom wall threaded onto the threaded stem 50 against the head member 47 and it protects the 40 thermally responsive member T from mechanical injury while permitting free access of the surrounding medium. The thermally responsive device T and mechanical advantage device M for controlling the tension link 59, are built into a 45 unit which is shown more clearly in Figures 5 and 6.

50 *The mechanical advantage device and the thermally responsive device*

55 The body of the thermally responsive device and the mechanical advantage device comprises a tubular stem 50 having a conical sealing surface 60, as heretofore described, for making a fluid-tight joint. This conical surface 60 is formed upon an enlarged head member 63 on the opposite side of which extend two flat ears 64-64. To the opposite sides of these two ears 64-64 a pair of plates 65-65 are riveted, these plates being preferably of metal. The plates 65-65 are spaced 60 apart by a block member 66 which is disposed substantially midway of the length of the plates 65. Registering slots 67 in each of the plates 65 extend from the left-hand end as viewed in Figures 5 and 6 to substantially the spacing block 66. This slot is to receive the tension link 59. A plurality of levers 68, 69, 70 and 72 are hinged or pivoted on pins which extend through the plates 65 and through the ends of the levers. These pins are placed close to the outer margins of the plates 65 and are indicated by the reference numerals 68', 69', 70' and 72', to correspond to the levers aforesaid. These levers form a compound 70 leverage system which provides a high multiplication of the mechanical advantage which this 75

mechanism obtains over the tension link 59. The tension link 59, is perforated as indicated at 73 (see Figure 6) and the levers, heretofore described, extend through this perforation. The 5 tension link 59 bears upon the first lever 68 intermediate its pivot and its free end. The free end of the lever 68 rests upon the lever 69 adjacent the pivot point of the lever 68. In turn, the free end of the lever 69 rests upon the lever 70 adjacent 10 its pivot point, and the lever 70 has its free end bearing upon the final lever 72 adjacent the pivot point of the latter. The final lever 72 is long enough to extend beyond the side plates. This lever 72 has its end slotted and pinched upon a 15 high tensile strength wire of small diameter shown at 74. A formed tubular guide member 75 lies partly between the plates 65—65 and extends between the ears 64—64 and is lodged in an enlarged portion of the bore within the stem 50. 20 Thus it forms a guide or conduit for the high tensile strength wire 74. This wire 74 is preferably a nickel-chromium-iron alloy wire such as chromel or nichrome. The stem 50 has a threaded part 51 which terminates in a neck 71 and has 25 a cap or cover member 78 sealing the end of the bore through which the wire 74 passes. The end of the neck 71 and inside of the cap 78 are oppositely coned to provide space for a button 80 of a 30 thermally sensitive alloy. This alloy is of a character to melt at approximately 100° C., that is, at a temperature below that at which the oil will form vapors or fumes which are ignitable.

The end of the fine wire 74 within the button 80 is formed into a hairpin turn, or hook, so as to anchor the wire therein. The alloy button 80 is 35 preferably cast in place, but it may be preformed upon the wire and the wire then inserted through the bore 79 and the guiding tube 75, and the cap 78 is thereafter fastened in place upon the neck 71 to form a fluid-tight seal. The rim of the cap 78 is preferably seated into a groove, or fluid 40 tightness may be secured merely by press fit. The alloy button 80, as above stated, is preferably cast in place, but it may be preformed, and provided with a slight neck to center the same suitably in 45 the open end of the bore 79.

The alloy button 80 is confined under considerable pressure between the cap 78 and the end of the neck 71 to bring these parts into good thermal contact. The button 80, while in good thermal 50 contact with the cap 78 and the portion of the neck contained within the cap, is nevertheless thermally quite remote from the adjacent mechanical structure. The guard 62, which serves to protect the device from mechanical injury, is also 55 directly supported in the oil, or other surrounding medium, and hence is fairly closely responsive to the temperature of the oil. However, it is thermally remote from the thermally sensitive element by the length of the interposed neck and the space between the barrel portion of the shield 62 and the cap 78. This button 80 is, therefore, 60 rapidly and closely responsive to temperature changes in the oil surrounding it.

The operations of the thermally responsive device and mechanical advantage device are as follows. The leverage system gives a mechanical advantage in the specific construction herein illustrated of approximately 150 to 1, although it 65 will be understood that this may be widely varied. The tension of the link 59 produced by the coil spring 52 tends, through the compound leverage system, to pull the wire 74 out of the button 80 in which the end is anchored. The anchorage 70 of the wire 74 in the button 80 by the hooked end

is such, however, that the button of alloy 80 must completely soften before the wire will be pulled out of the same. Thus, to a large extent, the mere bonding between the wire and the button such as would be presented by mere surface contact, and the uncertainty of operation connected therewith, is avoided. It is desirable in the operation of the power device that the resistance of the tripping mechanism and the alloy button 80 be not additive, otherwise the calibration of the 10 device might be effected by the wrong factor. It is for this reason that the plunger 54 has a lost motion connection with the trip or release member 43 so that the sole resistance to the initial expansion of the spring 52 is the thermally sensitive device T, as exercised through the mechanical advantage device. The tension in the link 59 comes mechanically through the levers upon the plate 65 and from the plate 65 upon the head 63 and the barrel head 47. Only a very small part 15 of said tension (in the present case about $\frac{1}{150}$ th) comes upon the thermally sensitive device T. Assume that the oil in the transformer casing in which the thermally sensitive device T is immersed reaches a temperature which is that for 20 which the alloy is designed to melt. Thereupon the alloy melts and the hooked end of the wire 74 is freed so that it may be drawn either through the bore 79 in hooked condition, or straightened out as it is drawn through the bore. This allows 25 the lever 72 to swing in a counterclockwise direction as viewed in Figure 5. It will be observed that as the leverage system begins to move it loses its ratio of mechanical advantage quite rapidly. That is to say, as the levers begin to 30 swing under the influence of the tension link 59, the free ends of the levers recede from the pivoted ends of the companion levers, thus reducing their ability to resist the tension of the link 59 and finally swinging clear of the link 59 and allowing the same to pass on to the last lever 72, which has merely the function of pulling the wire 35 74 through the bore of the guiding tube 75 to hold it. Therefore the initial motion of the spring 52 is devoted to insuring the release of the thermally sensitive device, and the succeeding motion of 40 expansion of the spring 52 is devoted to the tripping or operating of the release member 43.

Obviously, the amount of preliminary motion to ensure rupture of the bond of the alloy may be increased or the total stroke may be increased or diminished, as desired. In Figure 4 we have indicated the part of the stroke devoted to the bond rupture of the thermally sensitive device and the part of the stroke devoted to tripping the cutout. The dimensions and proportions may obviously 45 be varied.

After operation of the device, the clamping contacts 10—12 are released, and a new device is substituted by the operator. The actuating device is thereupon restored to working condition in 50 the shop or factory by replacing any parts which may have been damaged by opening of the circuit or otherwise, supplying a new thermally sensitive button 80 and wire 74, resetting the mechanical advantage device to tension link 59, the plunger 54 and the spring 52, closing the contacts of the interrupter and holding them by means of the clutch device, and supplying a suitable charge of arc extinguishing material.

Whereas, in the device just described, the interrupter with its thermal control and intermediate mechanism is mounted directly in the tank, the interrupter may advantageously be placed outside the tank and the thermally sensitive element, 70 75

with or without the power device, disposed in the tank in the oil through the temperature of which it is to be responsive. Thus, as shown in Figures 7 and 8, the interrupter I may be disposed in a 5 separate tank, the temperature responsive device and the power element, which are disposed in the transformer oil tank, being provided with a mechanical transmission, or other suitable form of transmission, to produce operation of the interrupter when the thermally sensitive device 10 responds to a dangerous oil temperature.

Separated thermally responsive device and interrupter

15 Referring now to Figures 7 and 8, the interrupter I is mounted in a pair of split clamp contacts 10—12 which may be identical with those shown in Figures 1 and 2, the lower clamp contact 10 being mounted upon a suitable bracket member 82 which is connected at its lower end to a conductor 83 extending through the insulating bushing 84 leading to the outside of the auxiliary tank 4. The upper clamp contact 12 is mounted upon another bracket, such as 85, which also, in turn, is mounted upon a conductor 86 extending through an insulating bushing 87 in the wall of the main tank 1. The conductor 86 is a hollow conductor providing a passageway through which extends a push rod 88 forming the mechanical transmission between the power element and the 20 release element of the interrupter I. An electrical terminal 89 is connected to the end of the hollow conductor 86, this terminal 89 being adapted to be connected to one of the transformer windings.

30 The brackets 85 and 82 are braced with respect to each other by a bar of insulating material such as 90 and the clamps 10 and 12 may also be braced with respect to each other by a similar bar of insulating material 92. These bars also 35 form guides to facilitate the introduction of the interrupting units within the clamp contacts 10 and 12 and to register the releasing mechanism of the interrupter with the push rod 88.

40 The interrupter, with its clutch and release members, is substantially identical with the corresponding mechanism described in connection with Figures 1 to 6. However, instead of threading the power unit stud directly into the opening in the side walls of the ferrule extension 22, the 45 stud threaded neck is now aligned by a coupling sleeve 93 with the hollow conductor 86 so that the plunger 54 of the power element is now aligned and in operative relation to the push rod 88. The power element and thermally sensitive element are identical with the corresponding structures heretofore described. The releasing fork 43 is, in Figure 7, connected to a thrust rod 94 guided in the bore of a tubular member 95 which has a threaded neck 96 like the corresponding part of the barrel 45. This threaded neck 96 is threaded into the opening in the side wall of the ferrule extension 22 and the outer end of the rod 94 is registered with the push rod 88. The outer end of the rod 94 is sealed to the tubular member 95 by a corrugated bellows 97, of metal, one end of which is beaded and, if desired, soldered to the fitting 95 and the other end of which is secured to the end of the thrust rod 94. The thrust rod 94 preferably has a head or enlargement 98, with a spring 99 of sufficient strength only to hold the rod 94 and the release fork 43 in normal position. A plate 100 may cover the end of the push rod 88 for engagement by the end of the thrust rod 94. A suitable guard or

5 housing 102 surrounds the metal bellows 97, this guard having a head 103 with a suitable aperture 104 through which the thrust rod 88 may project in operating the device.

10 The operation of this device is like that of the device of Figures 1 to 6 in all essential respects, as modified by the interposition of the transmission, and the necessity for sealing off the unit from the transmission. The fitting 95 is threaded in fluid-tight relation into the opening in the ferrule 22 and the flexible bellows 97 seals off the end of the rod 94 so that the interrupting unit is sealed fluid-tight. The guard 102 may act not only to protect the metallic bellows 97 from external injury, but also may limit the outward travel of the 15 rod 94 to protect the bellows from overextension. Thus the temperature responsive element T, which is directly responsive to the oil temperature in the transformer tank, in turn releases the tension link of the power element P, and the power 20 element, after first insuring breaking of the bond of the thermally responsive element, then proceeds to operate the thrust rod 88 and it, in turn, operates the corresponding rod 94 which is connected to the release fork 43. The remainder of 25 the operation is as described in connection with the operation of the interrupter unit heretofore recited. It is to be observed that there is a lost motion between the plunger 54 and the operating 30 rod 88. Obviously, such lost motion may be interposed between the rod 88 and the plunger rod 94, but preferably lost motion is at the former location, so that the power element may first free itself from the bond of the thermally responsive means and then proceed to institute operation 35 of the interrupter.

Remote control and gang operation

40 This modification is illustrated in detail in Figures 9, 10 and 11. In this construction the thermally sensitive element T releases the power element P which exerts a pull upon the cable 7 and this trips a mechanical relay R for tripping the interrupters or cutouts I, one of which may be connected in each phase of a three phase circuit, 45 for example, which is connected to a three phase transformer.

50 There are three interrupters, one in each phase lead to the transformer windings. If the transformer windings are disposed upon a common core and in a single bath of oil, then a single thermally sensitive element T and power element P control the relay mechanism for tripping the interrupters in all three phases. If, however, the transformer bank comprises three single phase 55 transformers, then a thermally sensitive element is placed in each of the transformer tanks and any one of the thermally sensitive elements, operating through the relay mechanism, is capable of opening the interrupters in all three phases.

60 One of the insulators 8 which supports the interrupters I is shown in elevation in Figure 9. They are connected to a supporting plate 15 which, in turn, is secured to the side wall of the tank 6. The insulator 8 has a pair of angularly 65 shaped brackets, more clearly shown in Figure 9, the horizontally extending portions of which clamp the conductor bar 115 between them for connection with the cable lugs of the cable leads. The bracket 116 is an L-shaped bracket, one part 70 of which, namely, the vertical part, is clamped to the insulator 8 and the horizontal part to the bottom of the bar 115. The bracket 117 likewise has a vertical portion clamped to the insulator 8 and a horizontal portion clamped to 75

the bar 115, and a further substantially vertical portion 118 the upper end of which is connected electrically and mechanically to the split clamp contact 12. The horizontal portion of the bracket 117 forms a perch or seat for an angular bearing bracket 119, this bracket being formed of L-shaped plate of sheet stock having a base portion and a vertical portion. The base portion is clamped to the bracket 117 and is thereby supported upon the insulator. The vertical part of the bracket 119 is substantially rectangular, and it has a central opening providing a bearing for the bakelized shaft 122. This shaft is common to the three phases. Similar brackets 119A and 119B also provide bearing support for the shaft 122. Between the brackets 119 and 119B, an operating or reset handle 123 is provided. A flanged metal bearing collar 124 is fastened upon the shaft 122. The flanged bearing sleeve 124 is held upon the Bakelite shaft 122 by a pair of screws 125-125 which screws also hold the ratchet collar 126 upon the said bearing sleeve 124. The collar 124 has a tooth 127 which is adapted to be engaged by the latch or detent 128 to hold the shaft 122 against rotation in a counter-clockwise direction as viewed in Figure 9. The latch or detent 128 is in the form of a bell crank pivoted at 129 upon the vertical part of the bracket 119. The free arm of the bell crank is pivoted on a pin 130 which is connected to the Bakelite link or rod 132. A retrieving spring 133 is connected between the actuating arm of the bell crank 128 and the base of the bracket 119. This spring thereby tends to hold the latch of the bell crank in position to be engaged by the tooth 127. When the rod or link 132 is pulled upwardly against the tension of the spring 133, the latch 128 is released from the detent 127, thereby releasing the shaft 122 for rotation in a counter-clockwise direction as viewed in Figure 9. A trip hammer 134, shown in detail in Figure 11, having a head or striker 135 and a hub 136, is mounted upon the bearing sleeve 124. The hub 136 fits loosely upon the bearing sleeve 124 but is compelled to turn with the shaft 122 and bearing sleeve 124 by virtue of the screw pin 137 which extends through a slot 138 in the hub member 136 and is secured to the bearing sleeve 126 on the shaft 122. Thus a small amount of angular play, as provided by the slot, is permissible between the trip hammer 134 and the operating shaft 122. The trip hammer 134 has a stop shoulder 139 which is adapted to engage a pin 120 secured in one corner of the vertical plate of the bracket 119. The head or striker 135 is aligned with the opening 104 of the casing 102 of the sealed release rod 94 which trips the interrupters I.

A coil spring 140, having one end engaging the bracket 119 and the other end engaging the trip hammer 134, is normally under stress tending to turn the shaft 122 in a counter-clockwise direction as viewed in Figure 9.

It can now be seen that by an upward pull on the rod or link 132 the bell crank latch 128 is swung out of engagement with the tooth 127, releasing the shaft 122 which, under the action of the spring, rotates the shaft counter-clockwise as viewed in Fig. 9, to cause the head or striker 135 of the trip hammer 134 to engage the head of the rod 94 and this, in turn, pushes the release fork 43 to the left as viewed in Figure 4, thereby allowing the clutch balls 42 to drop into the recesses 44 and release the movable plunger rod of the interrupter to open the circuit. The spring may be reset by bringing the handle 123

in a clockwise direction as viewed in Figure 9 to bring the detent tooth 127 under the latch 128.

The shaft 122 bears three similar trip hammer mechanisms, as will be apparent from Figure 10, so that when the latch 128 releases the dog or tooth 127, the rotation of the shaft 122 permits each of the trip hammers to strike its corresponding clutch release mechanism and cause operation of all three interrupters. Each of the trip hammers 134 is provided with its individual spring and each trip hammer has a lost motion connection through a slot and pin 138-137, shown and described particularly in connection with Figure 11. This permits the device to be assembled without requiring too great accuracy in angular alignment of the parts.

The link or rod 132 is pin jointed at its upper end to an arm 140 through the pin or pintle 142. The inner end of the arm 140 is pinned or keyed to the horizontal shaft 143, which shaft is common to three control cables 7. The shaft 143 is supported in a pair of bearings 144-145 mounted at the ends of a bearing plate 146 which is, in turn, mounted upon the upper end of an angle bar 147, the upper end of which, as indicated at 148, may be flattened out into a common plane for providing a rigid frame or backbone between the frame 146 which supports the shaft 143 and the plate 15 (see Figure 9) which supports the shaft 122 and its mechanism. The angle bar 147 thus spaces the two operating shafts to maintain them in proper alignment and spacing, and it, in turn, is secured to the inside of the housing or casing 6. There are three operating arms 148-149-149 for the three thermal control elements indicated in this construction, each of which is provided with a suitable clamp 150 for connecting to a corresponding cable 7. The clamps 150 comprise a body portion 151 pivotally connected to the end of the corresponding lever arm, a corresponding channel-shaped clamping member, and a pair of bolts provided with wing nuts for drawing the parts 151 and 152 together. This clamp is provided in order to permit of suitable adjustment of tension of the cables 7. The cables 7 extend through conduits such as 153 to the individual transformer tanks, the conduits being bent to any desired configuration and being provided at their ends with clamping flanges 154 for attachment to corresponding bosses 155 on the tank 6. At their opposite ends the conduits or pipes 153 are cut off to the desired length and fastened as by means of a compression coupling 156 to the corresponding clamping flange 157 on the corresponding transformer housing 1. The clamping flange 157 has a hollow stud 158 extending through a hole in the top of the transformer tank, that is, through the cover 159, a spool shaped button 160 being secured upon the end of the cable and, when the adjustment thereof with the extension of the cable is proper, the button 160 is drawn against the end of the boss 158. The thermally sensitive element T and the power element P are mounted upon the boss 158 and suitably connected to the button 160. The thermally sensitive element is constructed as shown in Figures 5 and 6. The stem 49 is extended through a flanged collar 162, a compression spring 163 bearing at its lower end against the flange of the collar 162, tending to throw the flanged collar and connected parts downwardly by the expansive force of the spring. A tubular sleeve 164 is secured to the collar 162 and extends upwardly through a fixed collar 165 which 75

collar is secured on the inside of a tubular frame member 166. The tubular frame member 166 is threaded at its upper end on the boss 158 for suitable mechanical support.

5 The side plates 65 of the mechanical advantage device carry the compound lever system as described in connection with Figures 5 and 6, held normally in place by the wire 74 and the alloy button 80, and these parts retain the tension link 59, the upper end of said tension link being anchored to the tubular support 166 by a cross pin 167 extending through the side walls of said tubular support 166. The upper end of the sleeve 164 is connected to a U-shaped tension member 168, the arms of which are connected to the upper end of the tube or sleeve 164 and the bottom of the U is apertured and has the stem 169 of the button member 160 extending loosely therethrough. An adjustable collar 170 is fastened on the lower end of the stem 169 to provide the lost motion desired for permitting the mechanical advantage device and the power spring to become released by rupture of the bond in the fusible alloy before the load of tripping the mechanical relay device, which actuates the three interrupters, occurs. A suitable cushion or buffer 172 on the upper end of the collar 165 serves to stop the downward motion of the sleeve 164 and to take up the impact of the blow.

20 When the temperature of the oil 5 into which the thermally responsive device T dips, reaches a temperature which melts the alloy bond, the wire 74 which holds the lever system is released and the tension link 59, under the influence of the power spring 163, releases the lever system and hence the flanged collar 162, carrying the collar, the thermally sensitive device, and the side frames 65 with the lever system, downwardly, as viewed in Fig. 9. This pulls the sleeve 164 downwardly and it, in turn, carries the U-shaped tension link 168 down on the stem 169 until the collar 170 is engaged, whereupon the power spring 163 exerts a pull upon the cable 7. The cable 7, acting on the crank arm 149, turns the shaft 143 is a clockwise direction, as viewed in Figure 9, swinging with it the arm 140 and raising the rod or link 132. It is to be observed that the pull on any one of the three cables is not influenced by the pull on any one of the other cables for the reason that when one cable 7 is pulled to the left, as viewed in Figure 9, the other cables merely slack their tension, and no interference results.

25 55 When the link 132 is pulled upwardly the detent 128 is swung out of the path of the dog or tooth 127 on the shaft 122 and the shaft 122, under the influence of the helical springs, is rotated in a counter-clockwise direction as viewed in Figure 9, throwing the hammers into engagement with the shafts or plungers 94 of the three interrupting units, thereby producing a simultaneous release of the movable plunger contact in each, with resultant interruption of the circuit and disconnection of the three phases from the transformer.

30 60 The power element shown in Figure 9 has the same two stages of motion described in connection with Figures 1 to 6, inclusive, so that the power element may free itself from the linkage and restraining effect of the levers and the wire 74 before taking on the tripping function, in this case of the relay mechanism.

70 75 While we have shown the circuit interrupter as controlled by a thermally sensitive element,

it will be observed at once that the organization of parts, from the switch contacts back through the control mechanism to the thermally sensitive button, is suitable for operation under the control of any other phenomenon. From beyond the sensitive button 80 to the circuit contacts, the entire organization of parts is useful of itself, and may be controlled by other control means, or even be under hand control. We do not therefore intend to limit the claims herein to thermal control, nor in fact to any specific control unless the same is specifically recited.

75 10 We do not intend to be limited to the details shown and described, except as the same are specified in the appended claims. We intend to cover all modifications which would occur to those skilled in the art, within the spirit and scope of our invention.

We claim:—

1. In a device of the class described, the combination of a switch having a movable switch member, latching means for holding said movable member in predetermined position, means tending to move said movable member, a normally stressed spring for disabling said latching means, means comprising a lever for holding said spring in stressed condition, and thermally sensitive means controlling said holding means comprising a tension strand connected at one end to said lever and a body of fusible alloy holding 30 the other end of the tension strand.

2. As an article of manufacture, a completely enclosed switch unit, said unit comprising a main tubular housing, a pair of arcing terminals therein, one of the terminals being movable, a spring 35 for moving said terminal longitudinally of the housing, a holding member having transversely movable release means extending laterally through a wall of said housing, and a supplemental housing joining the main housing and 40 providing a fluid-tight closure for said release means.

3. In a device of the class described, the combination of a tubular housing open at one end, a recombining chamber communicating with said one end thereof, a stationary arcing terminal adjacent said one end, a movable rodlike arcing terminal normally in conductive relation to said stationary terminal, a transverse partition adjacent said one end, said partition having an 50 opening through which said movable terminal projects, means to move the movable terminal, holding means for said movable terminal resting upon said partition, a release member movable transversely of said movable terminal, and 55 arc extinguishing material in the housing in position to be acted upon by the arc formed upon separation of the terminals.

4. In a device of the class described, the combination of a tubular closed housing, a stationary arcing terminal, a movable rodlike arcing terminal normally in conductive relation with said stationary terminal, means to move the movable terminal away from the stationary terminal, a transverse partition having a tubular bore through which said rodlike terminal projects and through which it is drawn upon separation of the arcing terminals, detent means for holding the movable terminal against movement, release means for said detent means, and arc extinguishing material adapted to act upon the arc in said tubular bore.

5. In combination for use with a transformer having a casing, a body of oil in the casing, and a winding in the oil, of an enclosed circuit breaker 75

- adapted to be connected in series with the transformer winding, a mass of fusible metal of low melting point adapted to be disposed in said body of oil, and mechanical trip means for the 5 circuit breaker controlled by said mass of fusible metal.
6. In combination for use with a transformer having a casing, a body of oil in the casing, and a winding in the oil, of an enclosed circuit breaker adapted to be connected in series with the transformer winding, a mass of fusible metal of low melting point adapted to be disposed in said body of oil, mechanical trip means for the circuit breaker controlled by said mass of fusible metal, 10
- 10 said circuit breaker comprising a tubular housing having external ferrules, and means adapted to be disposed outside the transformer for supporting the circuit breaker upon said ferrules.
7. In combination, a closed housing, a pair of 15 separable contacts, a spring for separating the contacts, means for restraining said spring comprising a clutch within the housing, a rod for releasing said clutch extending through a wall of said housing, and metallic means for sealing said 20 25 rod in fluid tight relation to said housing.
8. In combination, a tubular housing having a ferrule at each end, a stationary contact within one ferrule, a movable contact engaging the first contact, a spring between said movable contact 30 and the other ferrule, a clutch for holding the movable contact, said one ferrule having an opening through the wall thereof, and a clutch releasing member extending through said opening.
9. In combination, a tubular housing having a 35 ferrule at each end, a stationary contact within one ferrule, a movable contact engaging the first contact, a spring between said movable contact and the other ferrule, a clutch for holding the movable contact, said one ferrule having an 40 opening through the wall thereof, a clutch releasing member extending through said opening, arc extinguishing material in said housing, and a recombining chamber connected to the upper end of said ferrule.
- 45 10. In combination, a tubular sleeve having a metal ferrule at each end, an annular stationary contact in one ferrule, a transverse partition supported in said ferrule below said stationary contact, said partition having a passageway therethrough forming an arc confining bore, a 50 clutch sleeve resting upon said partition, clutching means mounted in said sleeve, a rodlike terminal extending through said passageway and sleeve and being engageable by said clutching means to hold the rodlike terminal in engagement 55 with the stationary terminal, a spring for said rodlike terminal, transversely movable release means cooperating with said clutching means, and means extending through the wall of the 60 said ferrule for operating said release means.
11. In a device of the class described, a sleeve of insulation, a ferrule on the upper end of the sleeve, a bushing of insulation secured in the ferrule adjacent said sleeve, a movable rodlike 65 terminal projecting up through said bushing, said terminal having a groove, a stationary terminal, said movable terminal engaging said stationary terminal, a sleeve surrounding said rodlike terminal and resting on said bushing and 70 guided thereby, said sleeve having openings therethrough, clutch bodies lying in said openings and extending into said groove, a yoke embracing said sleeve and holding said clutch bodies in said groove, means extending through a wall of the 75 ferrule for moving said yoke to release said bodies, and a spring for moving the movable terminal away from the stationary terminal.
12. In combination, a stationary contact, a movable contact, a spring for moving the movable contact, a detent for holding the movable contact against movement by the spring, a release member for releasing the detent, said release member having a lost motion, a spring for moving said release member, a thermally releasable restraining element for restraining movement of 10 said release member, the lost motion of said release element ensuring complete release of said release member from said restraining member before said release element releases the detent. 15
13. In combination, a movable member biased to move when released, a releasable detent means therefor for restraining the member against movement, a thermally responsive element comprising a thermally sensitive body which changes its consistency upon rise of temperature, a plunger biased for motion, a lost motion transmission operated by said plunger to release said detent and holding means for said plunger controlled by the condition of said thermally sensitive body. 20
14. In combination, a movable member biased to move when released, a releasable detent means therefor for restraining the member against movement, a thermally responsive element comprising a thermally sensitive body which changes its consistency upon an elevation of 25 temperature in response to externally applied heat and which is free from current flow therethrough, a plunger biased for motion, a mechanical relay means for releasing said detent, a lost motion transmission operated by said plunger for 30 controlling said mechanical relay means, and holding means for said plunger controlled by the consistency of said thermally sensitive body. 35
15. In combination, a plurality of automatic circuit breakers, a corresponding plurality of 40 releasable means for controlling the actuation of said circuit breakers, mechanical relay means for actuating said plurality of releasable means simultaneously, a thermally responsive element comprising a thermally sensitive body which 45 changes its consistency upon elevation of temperature, said thermally responsive element being disposed in non-conducting relation with respect to current flow through said circuit breakers, a plunger biased for motion, said plunger by its movement controlling said mechanical relay means, and holding means for said plunger controlled by the consistency of said thermally sensitive body. 50
16. In combination, a thermally sensitive body 55 of material the mechanical strength of which decreases upon the attainment of an elevated temperature in response to externally applied heat, means having relatively high thermal conductivity for sealing said thermally sensitive body from and rendering it quickly responsive to the ambient atmosphere, a lever restrained in controlling position by the body in its normal condition and adapted to be moved to non-controlling position, a tension link controlled by the lever, a 60 power device restrained from action by the tension link, and a releasing member adapted to be actuated by the power device. 65
17. In combination, a thermally sensitive body 70 of material of relatively light mass the mechanical strength of which decreases upon the attainment of an elevated temperature in response to externally applied heat, a lever restrained in controlling position by the body in its normal condition and adapted to be moved to non-controlling 75

position, a tension link controlled by the lever, a power device restrained from action by the tension link, and a releasing member adapted to be actuated by the power device, said power device having two successive stages of action, the first stage of action tending to move the lever to non-controlling position and the second stage of action tending to actuate the releasing member.

18. In combination, a thermally sensitive body of material the mechanical strength of which decreases upon the attainment of an elevated temperature, said body being disposed to be melted when the ambient temperature reaches approximately 100° C., a strand held by said body in the normal condition of said body and adapted to be released by decreased strength of said body, a link, a device restraining the link under the control of said strand, said device giving said strand a relatively large mechanical advantage over said link, a spring actuated plunger restrained by said link, a spring for said plunger, a circuit controlling member biased to move from a first position to a second position, and a restraining member for holding said circuit controlling member in one position and being controlled by said plunger.

19. In combination, a spring barrel having a head, a spring actuated plunger extending out of the barrel, a spring between the head of the barrel and the plunger, a tension member connected to the plunger, a self-releasing detent connecting said member to said head, a tension strand controlling the self-releasing detent, and a button of thermally controlled material disposed on the outside of said head and normally holding the tension strand against movement, said material being softened upon reaching an elevated temperature to release said strand.

20. In combination, a spring barrel having a head, a spring actuated plunger extending out of the barrel, a spring between the head of the barrel and the plunger, a tension member connected to the plunger, a self-releasing detent connecting said member to said head, a tension strand controlling the self-releasing detent, a button of thermally controlled material disposed on the outside of said head and normally holding the tension strand against movement, said material being softened upon reaching an elevated temperature to release said strand, a shiftable member and a lost motion connection between said plunger and said shiftable member, said lost motion connection permitting said plunger to release itself from the control of the strand before encountering the resistance of the shiftable member.

21. In combination, a stressed coil spring, a plunger adapted to be actuated by the spring, a member for holding the plunger against the stress of the spring, a strand, a mass of material the strength of which is decreased upon attaining an elevated temperature for holding said strand, said mass of material being disposed to be melted when the ambient temperature reaches that at which destruction of the insulation of transformer windings begins and a mechanical advantage device providing a high ratio of mechanical advantage for said strand over said member, said ratio being rapidly reduced as said member moves when said strand is released by said material said device being disposed within said coil spring.

22. In combination, a stressed spring, a plunger adapted to be actuated by the spring, a member for holding the plunger against the

stress of the spring, a strand, a mass of material the strength of which is decreased upon attaining an elevated temperature for holding said strand, said mass of material being disposed to be melted when the ambient temperature reaches that at which destruction of the insulation of transformer windings begins, a mechanical advantage device providing a high ratio of mechanical advantage for said strand over said member, said ratio being rapidly reduced as said member moves when said strand is released by said material, and means operated by said plunger only after predetermined motion of said member whereby the spring actuated plunger is substantially freed from the holding member before operating said last named means.

23. In combination, a rod having a recess therein, a stationary annular member embracing the rod and having an aperture registering with the recess, a holding body lying in the aperture and extending into the recess, a member for holding said body in said recess, said member being movable to a position to permit the body to move out of the recess to release the rod, a plunger for shifting said member to free the rod from the holding body, a spring for shifting the plunger, a link for holding the plunger against movement by the spring, and a body of fusible alloy for restraining the link.

24. In combination, a tubular sleeve of insulation having ferrule means at each end, the upper ferrule means having an extension of enlarged diameter at its upper end comprising a closed cooling chamber, switch contacts enclosed by the sleeve and ferrules, a laterally extending housing opening through the aforesaid ferrule extension of the upper ferrule, thermally sensitive means carried by said latter housing, and means subject to said thermally sensitive means for controlling the operation of said switch contacts.

25. In combination, a tank adapted to contain a body of liquid, a non-conducting bushing extending through one wall of the tank, a hollow conductor extending through said bushing, a thrust rod extending through said hollow conductor, a thermally sensitive element supported on said hollow conductor within the liquid in said tank, a plunger for operating said thrust rod controlled by said thermally sensitive element, a circuit interrupter having a closed housing comprising an insulating sleeve bearing external terminals in the shape of ferrules, means connecting the upper ferrule to said hollow conductor, terminal means connected to the lower ferrule, switch means within said interrupter housing, a detent for the switch means, and releasing means for the detent means extending through the housing and registering with said thrust rod.

26. In combination, a tank adapted to contain a body of liquid, a non-conducting bushing extending through one wall of the tank, a hollow conductor extending through said bushing, a thrust rod extending through said hollow conductor, a thermally sensitive element supported on said hollow conductor within the liquid in said tank, a plunger for operating said thrust rod controlled by said thermally sensitive element, a circuit interrupter having a closed housing comprising an insulating sleeve bearing external terminals in the shape of ferrules, means connecting the upper ferrule to said hollow conductor, terminal means connected to the lower ferrule, switch means within said interrupter housing, a detent for the switch means, and releasing means for the detent means extending

through the housing and registering with said thrust rod, and a metallic bellows for sealing said release means.

27. In combination with a tank adapted to contain a body of insulating liquid, a chamber formed on the outside wall of the tank, an insulating bushing extending between the chamber and the inside of the tank, a hollow conductor extending through the bushing, a circuit interrupter disposed in the chamber, said circuit interrupter comprising a closed tubular housing having contacts biased to open, detent means for holding said contacts in conducting relation, trip means for releasing said detent, thermally controlled means, and a member controlled by said thermally sensitive means extending through said hollow conductor for operating said trip means.

28. In combination with a plurality of tanks, circuit conductors extending to each of said tanks, thermally sensitive means in each of said tanks, a plurality of circuit breakers for controlling said circuit conductors, a common trip means for each of said circuit breakers, and transmission means between each of said thermally sensitive elements and said trip means.

29. In combination with a plurality of apparatus tanks, thermally sensitive elements in said tanks, a circuit interrupter tank containing a plurality of interrupters, one for each apparatus tank, each of said circuit interrupters having individual release means, a common actuating member for each of said release means, a trip member for said common actuating means, and means under control of each of said thermally sensitive elements for controlling said trip means.

30. In combination with a plurality of electrical circuit conductors, a corresponding plurality of circuit interrupters having individual trip means, thermally sensitive elements responsive to heat given off by said conductors, a common actuating member for said trip means, a single detent for said common actuating means, and a transmission from each of said thermally sensitive elements to said trip means including a plurality of flexible cables.

31. In combination, a plurality of circuit conductors, a corresponding plurality of circuit interrupters in series with said conductors, said circuit interrupters having individual trip means, a shaft provided with means for actuating said trip means simultaneously, spring means for actuating said shaft, a detent for holding said shaft against movement by said spring means, a thermally sensitive element responsive to heat given off by said circuit conductors, a power unit for each thermally sensitive element, a second shaft, a connection between said second shaft and said detent for releasing said shaft to trip all of the circuit interrupters, and transmission means between said power unit and said second shaft comprising a flexible tension element.

32. As a means for opening an electrical power supply circuit upon the occurrence of predetermined thermal conditions in a body related to said circuit, the combination of a compact high duty circuit breaker comprising a pair of separate contacts provided with arc extinguishing material and with operating means tending to separate said contacts, a detent holding said operating means from acting, actuating means for moving the detent to releasing position, and means comprising a body of fusible material for normally restraining said actuating means and adapted, upon attaining a predetermined temperature, to

release said actuating means to cause release of the detent and operation of the circuit breaker.

33. In combination, a normally closed circuit breaker having a first spring biased to operate the circuit breaker, a detent for holding the spring, a mechanical trip for the detent, a second spring biased to actuate the trip, and restraining means for the second spring comprising a body of fusible metal which when melted releases the spring restraining means, allowing the second spring to actuate the trip which holds the first spring, and the first spring, in turn, operates the circuit breaker.

34. In combination a closed tubular housing, a stationary contact disposed therein adjacent one end thereof, means within said housing providing an arcing bore adjacent said stationary terminal, a plunger having a contact at one end engaging said stationary contact, said plunger lying within said arcing bore and disposed wholly within said housing, a stressed spring connected to said plunger for retracting the same endwise of said bore, detent means within the housing for holding said plunger against the stress of said spring, release means for said detent means extending through a lateral wall of the housing, and arc extinguishing material within the housing acting upon the arc drawn in said bore to extinguish the same.

35. In combination a tubular sleeve of insulation having ferrules forming external terminals, a stationary switch terminal within and connected to one ferrule, a spring anchored to the other ferrule, a plunger disposed wholly within the housing having one end connected to the spring and the other end in engagement with said stationary contact, a releasable holding device for holding the plunger, said device being supported by said one ferrule, and a release member for said device extending through a lateral opening in the said one ferrule.

36. In combination for use with a transformer having a casing, a body of oil in the casing, and a winding in the oil, a circuit breaker having contacts adapted to be connected in series with the transformer winding, a housing for said circuit breaker, a mass of fusible metal of low melting point adapted to be disposed in said body of oil out of current conducting relation with respect to said contacts, mechanical trip means controlled by said mass of fusible metal for releasing said contacts for movement to the open position, and liquid arc extinguishing material in said housing adapted to react with the arc formed between said contacts on separation for assisting in extinguishing it.

37. In a device of the class described, the combination of a tubular housing open at the top end, a recombining chamber communicating with said top end, a stationary arcing terminal adjacent said top end, a movable rodlike arcing terminal normally in contact engagement with said stationary terminal, a transverse partition underneath said stationary terminal having an opening through which said movable terminal projects, means for biasing said terminals apart, a release member for said movable terminal movable transversely relative thereto, a body of arc extinguishing liquid in the lower portion of said housing, and a liquid director slidably mounted on said arcing terminal and movable therewith after a predetermined movement thereof for directing said liquid in position to be acted upon by the arc formed upon separation of the terminals.

38. In a device of the class described, the com-

bination of a tubular closed housing, a stationary arcing terminal, a movable rodlike arcing terminal normally in conductive relation with said stationary terminal, means to move the movable terminal away from the stationary terminal, a transverse partition having a tubular bore through which said rodlike terminal projects and through which it is drawn upon separation of the arcing terminals, detent means for holding the movable terminal against movement, release means for said detent means, and liquid arc extinguishing material in said housing adapted to react with the arc formed between said terminals on separation thereof for assisting in extinguishing it.

39. In combination a fluid tight tubular housing, a stationary contact member disposed therein adjacent one end thereof, a movable contact member disposed wholly within said housing for engaging said stationary contact member, a tension spring disposed within said housing for biasing said movable contact member away from said stationary contact member, detent means within said housing for holding said contact members in engagement, release means for said detent means extending through a lateral wall of said housing, and bellows means surrounding said release means and secured in fluid tight relation to said housing for maintaining the fluid tight integrity of said housing and permitting operation of said release means by an externally applied force.

40. For combination with a plurality of circuits disposed to connect a load device to a cur-

rent source, a circuit interrupter of the single shot blast type interposed in each of said circuits, a fluid tight housing for individually enclosing each of said circuit interrupters, externally operable tripping means sealed in each of said housings for tripping the circuit interrupters enclosed thereby, fault responsive means individual to each of said conductors, and means responsive to the operation of any one of said fault responsive means for simultaneously operating all of said tripping means to completely disconnect said load device from said current source.

41. For combination with a plurality of circuits disposed to connect a load device to a current source; a shelf contained circuit interrupter interposed in each of said conductors comprising a pair of separable contact members disposed on separation to draw an arc therebetween, arc extinguishing material disposed to form a blast for extinguishing said arc, and externally operable tripping means for normally holding said contact members in engagement, the contact members of each circuit interrupter being mechanically independent of the contact members of any other circuit interrupter; fault responsive means individual to each of said conductors, and means responsive to the operation of any one of said fault responsive means for simultaneously operating all of said tripping means to completely disconnect said load device from said current source.

HUGH A. TRIPLETT.
